UNITED STATES PATENT OFFICE.

THOMAS J. STURTEVANT, OF WELLESLEY, MASSACHUSETTS, ASSIGNOR TO STURTEVANT MILL COMPANY, OF BOSTON, MASSACHUSETTS, A CORPORATION OF MASSACHUSETTS.

AIR-SEPARATOR.

1,385,025.

Specification of Letters Patent. Patented July 19, 1921.

Application filed May 15, 1919. Serial No. 297,291.

To all whom it may concern:

Be it known that I, THOMAS J. STURTEVANT, a citizen of the United States, residing at Wellesley, county of Norfolk, and 5 State of Massachusetts, have invented an Improvement in Air-Separators, of which the following description, in connection with the accompanying drawings, is a specification, like characters on the drawings representing like parts.

The invention to be hereinafter described relates to separators for grading materials, and more particularly to air separators. One form of air separator comprises inner 15 and outer chambers in communication with each other and having a fan for producing an air current which moves upward in the inner chamber and downward in the outer chamber. The materials to be graded are introduced in the path of the rising current in the inner chamber, and the lighter particles are carried upward by the rising current over into the outer chamber, while the heavier particles gravitate downward 25 through the rising current in the inner chamber. The lighter particles or fines are conducted from the outer chamber through one discharge passage, and the heavier particles or tailings are conducted from the 30 inner chamber through another discharge passage.

Sometimes it is desirable to classify the materials so that very fine particles will be separated, and sometimes it is desirable 35 to classify the materials so that coarser particles are separated. One of the purposes of the present invention, therefore, is to provide simple and efficient means for varying the openings between the inner and outer 40 chambers, so that the strength of the air current produced by the fan will be varied.

In use, certain of the internal parts of the separator become worn, and therefore, it is desirable to have ready access thereto 45 for the purposes of repair or replacement of the parts. Another purpose of the invention, therefore, is to provide a construction whereby the casing or casings inclosing the internal parts may quickly and readily be 50 removed when desired. In the present instance of the invention, the closure for the internal parts comprises an upper casing and a lower casing, the former being superposed on and the latter being arranged to

depend from a common foundation ring or 55 member, the construction being such that the upper casing may be readily lifted from said ring or member to disclose the parts contained therein.

It is desirable that the inner and outer 60 chambers and the openings affording communication between them shall be obstructed as little as possible, in order that the air current may pass freely therethrough with a maximum grading effect. Another 65 purpose of the invention, therefore, is to provide means for supporting and rotating the air current producing fan and a rotary device for distributing the materials to the rising current of air in the inner chamber 70 from beneath said fan and distributing device in a manner such that minimum obstruction is offered to the air currents.

Another object of the invention is to provide means for inclosing the driving mechanism for the fan and rotary distributing device so that the working parts of the driving mechanism are protected from dust, but are readily accessible when desired for purposes of inspection, replacement and repair. 80

The materials distributed by the rotary distributing device are thrown against a portion of the casing for the inner chamber with considerable force, and thereby produce a greater degree of wear thereon 85 than on other portions of the casing of the inner chamber. And another purpose of the invention is to provide a strong wear resisting baffle plate to receive the bombardment of the materials from the rotary distributor, said plate being detachably associated with upper and lower parts of the casing, so that it may be readily removed and a new baffle plate substituted therefor. 90

With the aforesaid and other purposes in view, the character of the invention will be best understood by reference to the following description of one good form thereof shown in the accompanying drawings, wherein:

Figure 1 is a vertical section through the separator shown herein as embodying the invention;

Fig. 2 is a horizontal section taken on line 2-2 of Fig. 1;

Fig. 3 is a horizontal section taken on line 3-3 of Fig. 1;

Fig. 4 is a plan of the portion of the ma-

100

105

chine beneath a horizontal plane cutting the axis of the main driving shaft on line 4-4 of Fig. 1;

Fig. 5 on an enlarged scale is a sectional detail of means for securing the rotary distributor device on the upper end of the vertical shaft for rotating the same; and

Fig. 6 is a view similar to Fig. 5 showing a jack screw substituted for the holding screw shown in Fig. 5, for freeing the rotary distributor device from the vertical shaft.

Referring to the drawings, the separator shown therein as one good form of the invention, comprises a supporting member, in the present instance of the invention, in the form of a ring 1 (Fig. 1) having feet 3 adapted to be secured by bolts 5 to beams 7 or other appropriate supporting means.

Mounted on a flange 9 of the foundation ring is an outer casing 11 for the outer chamber 13 and comprises a base ring 15 having an internal flange resting on the foundation ring flange 9 and detachably secured thereto by screw bolts 17. A shell 19, in the present instance of the invention, of cylindrical form has its lower edge riveted to the base ring 15 and its upper edge riveted to a top ring 21. A head 23 is secured by rivets to the top ring 21 and is provided with eyes 25 adapted to be connected to a suitable tackle which may be used for readily lifting the outer casing 11 from the foundation ring when desired.

Within and spaced from the outer casing 35 is an inner casing 27 for the inner chamber 28 and comprising an upper conical shell 29 and a lower conical shell 31. The inner ends of the upper and lower shells may be riveted or otherwise secured to rings 33 connected by through bolts 35. These rings are shouldered to receive a circular baffle plate 37 which may be of heavier and stronger material than the upper and lower shells 29 and 31. The construction is such that on release of the through bolts 35, the baffle plate 37 may be readily removed and a new one substituted therefor.

Encircling the lower shell 31 is a cylinder 39 having its upper edge riveted or otherwise secured to the lower ring 33, and its lower edge secured to a ring 41. Projecting from and conveniently integral with the ring 41 are a plurality of feet 43, in the present instance, three being shown having sockets 55 resting on the upper ends of posts 47 which project downward loosely through sleeves 49 formed on brackets 51 projecting inward from the foundation ring 1. The lower ends of the posts 47 rest on the upper ends of screws 53 threaded in bosses 55 on plates 57 secured to a conical casing 59 which serves as the discharge passage for the finer particles graded as more fully hereinafter described. The upper edge of the conical casing 59 may be riveted or otherwise secured

to the foundation ring 1, and the lower end of the conical casing 59 may have a discharge port 61. A ring 63 may be secured to the conical casing adjacent the lower end thereof and may be connected to piping (not shown) for conducting the finer particles to the point desired. The lower ends of the screws 53 may have square heads 65 to facilitate adjustment thereof. The construction is such that on rotation of the screws 53, the post 47 may be raised or lowered in their bosses 49 to elevate or lower the inner casing bodily as desired.

To conduct the tailings from the inner chamber, a mouth, in the present instance, in the form of a cylinder 67 may be provided having its lower edge riveted or otherwise secured to the upstanding flange of a ring 69 secured by bolts 71 to the inner ends of the brackets 51 referred to. A ring 73 has an outwardly projecting flange interposed between the ring 69 and the brackets and secured thereto by the bolts 71. To the ring 73 is riveted or otherwise secured a conical casing 75 which serves to discharge the tailings to a spout 77 connected to the lower end of the conical casing 75 and projecting through the wall of the fines discharge casing 59. A ring 79 embraces the lower end of the spout 77 and may be connected to suitable piping (not shown) for conducting the tailings to the point desired.

The materials to be graded may be introduced into the separator through a hopper 81 having an outwardly projecting flange 83 riveted or otherwise secured to the margin of the head 23 surrounding a central opening therein. Projecting downward from the hopper 81 is a pipe 85 for conducting the materials to the rotary distributor device.

The rotary distributor device, in the present instance of the invention, comprises a head 87 having a bottom plate 89 and an upstanding rim 91 provided with radial passages 93. An upper ring or distributing plate 95 is mounted on the upper edge of the rim 91 and secured thereto by screw bolts 97, and a lower ring or distributing plate 99 is mounted on the plate 89 and secured thereto by bolts 101.

The construction is such that materials flowing downward through the hopper 81 and pipe 85 will strike the plate 89 of the distributor and under the influence of centrifugal force will flow outward through the radial passages 93 and thence outward between the distributor plates 95 and 99 toward the baffle plate 37 referred to.

Suitable means may be provided to support and rotate the distributor device. To accomplish this, in the present instance of the invention, the head 91 of the distributor device is provided with a hub 103 having a tapered bore fitted on the upper tapered end 130

- portion 105 of a vertical shaft 107. To secure said hub to said shaft, a screw bolt 109 (Figs. 1 and 5) may have a head seated in a counterbore in the hub, and a shank entered in a threaded bore 111 in the shaft. The construction is such that when the screw bolt 109 is tightened, it will draw the hub 103 down securely to the tapered end of the shaft 107.
- 10 The weight of the rotary distributor device will tend to press the hub thereof so tightly onto the conical end of the shaft 107 that it may be difficult to free the hub from said shaft. To facilitate this, a jack screw 113 (Fig. 6) may be provided having a shank 115 threaded to a tapped hole 117 in said hub larger than the shank of the screw bolt 109 referred to, employed for securing the hub to the shaft. The jack screw has
- 15 a smooth reduced portion 119 adapted to enter freely through the tapped bore 111 in the shaft, so that its lower end may rest on the bottom of said bore. When it is desired to start the hub up from its shaft, the holding
- 20 screw bolt 109 is removed and the jack screw is substituted therefor. Rotation of the jack screw will cause the lower end to react against the bottom of the bore in the shaft, and the threaded shank 115 thereof will coöperate
- 25 with the portion of the hub threaded thereto to force the hub from the tapered end of the shaft. After the hub has been thus separated from the shaft, it may be readily lifted therefrom.
- 30 35 To produce the air currents for the purposes described, a fan may be provided, in the present instance of the invention, comprising a plurality of vanes 121 having flanges 123 riveted or otherwise secured to
- 35 40 a ring plate 125 encircling the hopper 81 referred to, and having its inner edge portion secured by bolts 127 to the outwardly flaring upper end of a sleeve shaft 129 encircling the pipe 85. The fan and sleeve shaft
- 45 50 may conveniently be rotated in unison with the rotary distributor device. To accomplish this, the lower end of the sleeve shaft is provided with an outwardly projecting flange 131 secured by the screw bolts 97 referred to, to the rim 91 of the rotary distributor device.
- The construction is such that the rotary distributor device, the sleeve shaft and the fan may be readily assembled and separated as desired.
- 55 To promote efficient operation of the fan and form a part of the housing therefor, a ring plate 132 (Fig. 1) may be provided having its inner edge riveted or otherwise secured to an angle ring 132^a riveted or otherwise secured to the upper edge of the shell 29 at the inner casing. The ring plate 132 will share in the bodily adjustment of the inner casing, and, for example, may be
- moved from its position shown in full lines 65 to its position shown in dotted lines when said casing is adjusted, and to other positions as required.
- Referring again to the vertical shaft 107 for rotating the distributor device and fan, 70 the lower end of this shaft may be mounted in an end thrust bearing 133 carried by the lower part 135 of a spherical gear casing connected to or integral with brackets 139 (Fig. 4) projecting inward from the ring 73 75 referred to, mounted on the brackets 51.
- The upper portion of the vertical shaft 107 may be journaled in a bushing 141 mounted in bearings 143 in the upper end of a gear casing 145 having at the lower end 80 thereof a portion 147 forming a part of the spherical gear casing referred to. Brackets 148 may be connected to or be formed integral with the upper part of the gear casing and the ring 73, referred to. The brackets 139 and 148 may be detachably connected by bolts 149.
- To prevent ingress of dust to the bearings 143, a hood 150 may be secured to the distributor hub 103 and overlap the upper end 90 portion of the casing 145.
- Suitable means may be provided to lubricate the bearings 143. To accomplish this, in the present instance, a pipe 151 may be provided having its upper end entered 95 through the casing 105 and communicating with an oil chamber 153, communicating in turn with the shaft 107 through ports 155 in the bushing for said shaft. The lower end of the pipe 151 projects outward through 100 the conical casing 59 referred to, where it receives an externally accessible grease cup 157.
- Suitable means may be provided to lubricate the end thrust bearing 133. To accomplish this, in the present instance, a pipe 161 is provided having its inner end entered through said bearing and communicating with the lower end of the vertical shaft 107. The outer end of the pipe 161 projects 110 through the conical casing 59, where it receives a grease cup 163.
- To rotate the vertical shaft, in the present instance of the invention, it is provided with a bevel gear 165 fast thereon meshing 115 with a bevel gear 167 fast on the inner end of a horizontal driving shaft 169 journaled in a split bearing having a part 171 integral with the lower part of the spherical casing, and a part 173 integral with the upper part 120 of the spherical casing. The parts 171 and 173 of this bearing may be detachably connected by bolts 175 (Fig. 4).
- Suitable means may be provided to lubricate the bearing parts 171 and 173. To 125 accomplish this, in the present instance, a pipe 174 is provided having an end projecting through the bearing part 171 to the

shaft, and an outer end projecting through the conical casing 59, where it receives a grease cup 174.

The horizontal driving shaft is also journaled in a split bearing having a part 177 integral with the foundation ring 1, referred to, and a part integral with the base ring 15 referred to, of the outer casing, the parts of this bearing being detachably connected 10 by bolts 183 (Fig. 4). The bearing parts may be lubricated by a grease cup 187.

To prevent dust from entering the bearings for the horizontal driving shaft, a sleeve 189 may be placed on said shaft and have 15 ends entered into counterbores in the bearings for said shaft and provided with packings 191. On the outer end of the horizontal driving shaft, a pulley 193 may be provided adapted to be driven by a belt 20 from any suitable source of power.

In operation, the materials to be graded are introduced into the hopper 81 and flow down through the pipe 85 until they strike the bottom plate 89 of the rotary distributor. 25 The materials pass under the influence of centrifugal force outward through the passages 93 and thence between the distributor plates 95 and 99 toward the baffle plate 37. The rotary fan produces an air circuit including an air current having an upward 30 movement through the inner chamber 28 as indicated by the arrows in Fig. 1, which meets the outwardly projected materials issuing from the distributor and carries the 35 lighter particles thereof outward between the vanes of the fan. The air current passes thence downward through the outer chamber 13 in the direction indicated by the arrows, and is drawn inward between the cylindrical mouth 67 and the lower end of the 40 inner chamber and rises thence again in said chamber. The lighter particles flow on downward in the direction indicated by the arrow into the conical discharge casing 59 and issue therefrom through the mouth 61. 45 The heavier particles drop down through the inner chamber, through the cylindrical mouth 67, through the conical discharge casing 75 and thence through the spout 77 and issue 50 from the mouth thereof.

If it is desired that a fine grading effect shall be produced, the lower opening should be reduced and the upper opening between the inner and outer chambers receiving the 55 fan should be enlarged. To accomplish this, the screws 53 are adjusted to lower the posts 47 and thereby bodily lower the casing for the inner chamber. This lowering movement of the inner chamber will not only enlarge 60 the opening receiving the fan, but also will reduce the opening between the lower end of the casing for the inner chamber and the upper end of the cylindrical mouth 67. The reduction of the latter opening, will re-

duce the strength of the air current passing 65 therethrough. The fines will not be drawn into the cylindrical mouth 67, since they tend to pass downward close to the shell 19 of the outer casing. The enlargement of the upper 70 opening increases the efficiency in separating finer particles since the fan acts on a larger body of air and produces more of a whirl of the air and eddy currents.

When it is desired to produce a classification of coarser grading effect, the screws are 75 adjusted to elevate the posts 47 and the casing for the inner chamber, thereby increasing the size of the lower opening and reducing the size of the opening receiving the fan. This draws a stronger current in through 80 the lower opening and up through the inner chamber. This stronger current will carry particles which are heavier than before outward between the vanes of the fan, and they will fall thence downward and be discharged 85 as previously described.

The casing for the inner chamber may be adjusted as desired while the separator is in operation, thereby facilitating the proper adjustment thereof to produce the character 90 of classification required.

If access is desired to the parts contained within the outer casing, the screw bolts 17 connecting the base ring of the outer casing with the foundation ring may be removed, 95 and the outer casing together with the hopper 81 and pipe 85 may be lifted from the machine by application of suitable tackle to the eyes 25 on the head of the casing.

If it is desired to remove the casing for the 100 inner chamber, the bolts 127 connecting the fan plate 125 with the sleeve shaft 129 may be removed to allow removal of the fan, and then the casing may be readily lifted upward from the posts 47, since the feet 43 for 105 the inner casing merely rest upon and are not secured to said posts. The distributor plates 95 and 99 are somewhat smaller in diameter than the diameter of the lower end of the inner casing, and therefore, do not interfere with the removal of the inner casing. 110

If it is desired to remove the rotary distributor, the sleeve shaft 129 is detached therefrom, thereby allowing ready access to the holding screw 109 for the purpose of removing the same from the vertical shaft. Then the jack screw may be applied as described to force the hub of the distributor from said shaft. Thereupon, the distributor may readily be lifted from said shaft. 115

If access be desired to the driving mechanism in the spherical casing, the bolts 71, 149, 175 and 183 may be removed, thereby allowing the upper part of the spherical housing and the upper parts of the bearings 125 for the horizontal shaft to be lifted upward away from the lower part of the spherical housing and the lower parts of the bearings

for the horizontal shaft. The separation of the parts thus accomplished will admit ready access to the bevel gears, the vertical shaft and the horizontal shaft, as desired.

5. By my invention a separator is provided which is simple and cheap in construction, the parts thereof may be readily separated or removed as desired, and materials may be classified efficiently to separate fines or coarse

10 particles as desired.

It will be understood that the invention is not limited to the specific embodiment shown, but that various deviations may be made therefrom, without departing from the 15 spirit and scope of the appended claims.

What is claimed is:—

1. A separator, comprising, in combination, outer and inner chambers communicating to allow an air circuit therethrough including upward air currents in one and downward air currents in the other, a foundation member for supporting said outer chamber, posts beneath the inner chamber projecting through said foundation member 20 for supporting the said inner chamber, and means longitudinally to adjust said posts to vary the elevation of the inner chamber in the outer chamber.

2. A separator, comprising, in combination, outer and inner casings, a foundation ring supporting said outer casing, brackets projecting inward from said foundation ring, posts slidably mounted in said brackets, feet for said inner casing resting 35 on said posts, and adjusting screws for sliding said posts in said brackets to vary the elevation of the inner casing.

3. A separator, comprising in combination, outer and inner casings, a fan for inducing an air circuit through said casings for grading materials, means to introduce the materials into the path of said air circuit, and a support for the lower end of the inner casing independent of the outer 45 casing, the inner casing being removable from said support.

4. A separator, comprising, in combination, outer and inner casings, a fan to induce an air circuit through said casings for grading materials, means to feed the materials to be graded in the path of said air circuit, a foundation member for supporting said outer and inner casings independently of each other, and means detachably to connect the outer casing with said foundation member, that the outer casing may readily be lifted therefrom to disclose the inner casing.

5. A separator, comprising in combination, outer and inner casings, foundation means supporting said casings, an upright shaft carried by said foundation means and projecting up into the inner casing, a rotary fan to induce an air circuit through said

casings for grading materials, means to connect said fan with said upright shaft and means adjacent the lower end of said shaft for rotating the same. 65

6. A separator, comprising in combination, a casing having separating and collecting chambers therein, foundation means supporting said casing, an upright shaft carried by said foundation means projecting up into said separating chamber and having a tapered portion, a rotary fan to 70 induce an air circuit through said casings for grading materials, a rotary distributor for delivering the materials into the path of said air circuit and having a tapered portion fitting the tapered portion of said shaft, 75 and a jack screw for co-operation with said distributor and shaft to force the former from the latter.

7. A separator, comprising in combination, foundation means, a casing above and mounted on said foundation means and having separating and collecting chambers therein, discharge casings carried by and depending from said foundation means for receiving materials from said chambers, a gear casing carried by said foundation means and having parts projecting above and beneath the same, an upright shaft journaled in bearings in said gear casing, and projecting into the separating chamber, 85 a horizontal shaft journaled in a bearing in said gear casing, gears on said shafts meshing with each other and located in said casing, and a fan and a distributor rotated by said upright shaft, said chamber containing 90 casing and the upper part of said gear casing being removable from said foundation means. 95

8. A separator, comprising in combination, outer and inner casings, an upright 105 shaft projecting into said inner casing, a rotary distributor mounted on said shaft, a sleeve shaft mounted on said rotary distributor, a fan carried by said sleeve shaft for inducing an air circuit through said 110 casings, and means to drive said upright shaft.

9. A separator, comprising in combination, outer and inner casings, an upright shaft projecting into said inner casing, a 115 rotary distributor mounted on said upright shaft, a sleeve shaft mounted on said rotary distributor, a fan carried by said sleeve shaft, and a feed chute depending from said outer casing through said sleeve shaft toward the distributor to feed materials thereto. 120

10. A separator, comprising in combination, outer and inner casings, an upright shaft projecting upward through the lower 125 end of the inner casing into and terminating in the interior thereof, a rotary distributor mounted on said shaft, a sleeve shaft

mounted on and projecting above said rotary distributer, a fan carried by said sleeve shaft, and means detachably to connect said sleeve shaft with said rotary distributer and 5 fan.

11. A separator, comprising in combination, outer and inner casings, an upright shaft projecting upward into and terminating in said inner casing, a sleeve shaft above 10 and carried by said upright shaft, a fan comprising a ring and vanes secured to said ring, and means detachably to connect said ring with said sleeve shaft.

12. A separator, comprising in combination, a foundation ring, brackets projecting inward from said ring, an outer casing mounted on and detachable from said foundation ring, posts projecting through said brackets, adjusting screws for said 20 posts, a cylinder having feet resting on said posts, an inner casing carried by said cylinder, an upright shaft carried by said foundation ring and projecting into said inner casing, a rotary distributer mounted on said 25 shaft, and a fan rotated by said shaft for inducing air currents upward past said distributer to grade materials delivered therefrom.

13. An air separator, comprising, in combination, an outer cylindrical casing of substantial depth, an outer conical casing projecting downward therefrom and provided with a fines delivery outlet, an inner casing comprising a cylindrical baffle wall portion 30 and conical wall portions projecting above and beneath the cylindrical baffle wall portion, an inner conical casing beneath the inner casing having a tailings delivery outlet, the upper end of the inner casing being 35 spaced somewhat from the upper end of the outer casing, said inner casing containing a separating chamber, and said inner casing being spaced from the outer casing to provide a collecting chamber, means to support 40 the inner casing from the outer conical casing, a fan in the space between the upper 45

end of the inner casing and the upper end of the outer casing for causing an air current to move upward in the separating chamber and downward in the collecting chamber, 50 an upright shaft projecting into the separating chamber, a rotary distributer carried by said shaft in opposition to the cylindrical portion of the inner casing, and a feed chute projecting from the upper end 55 of the outer casing toward the distributer for delivering materials to the latter, that they may be thrown outward into the path of the air current rising in the separating chamber. 60

14. An air separator, comprising an outer cylindrical casing of substantial depth, a conical casing projecting downward from the outer cylindrical casing and provided with a fines discharge outlet, an inner casing having a baffle wall and a conical portion projecting upward from the baffle wall, said inner casing having a separating chamber therein, and said inner casing being spaced from the outer casing to form a collecting 70 chamber between them communicating with the upper and lower ends of the separating chamber, means to support the inner casing independently of the outer cylindrical casing, that said means may not obstruct the 75 collecting chamber, an upright shaft projecting into the separating chamber, a fan carried by said shaft for causing an air current to move upward in the separating chamber and downward in the collecting 80 chamber, a rotary distributer carried by said shaft, and a feed chute projecting down from the top of the outer casing toward the rotary distributer for delivering materials to the distributer, that they may be thrown 85 outward thereby toward the baffle wall into the path of the air current moving upward in the separating chamber.

In testimony whereof I have signed my name to this specification.

THOMAS J. STURTEVANT.
